CLAIM

The ornamental design for a case for electronic communications device as shown and described.

DESCRIPTION

FIG. 1 is a front perspective view of a case for electronic communications device showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof; and,

FIG. 9 is another rear elevational view thereof shown with an environmental card.

The broken lines in the drawing figures form no part of the claimed design; they depict an environmental card and portions of the case for electronic communications device that form no part of the claimed design.

1 Claim, 9 Drawing Sheets
